(57) **CLAIM**

The ornamental design for a portable industrial light, as shown and described.

DESCRIPTION

FIG. 1 is a top right perspective view of a portable industrial light in accordance with my invention;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The broken lines in the drawings illustrate portions of the portable industrial light which form no part of the claimed design.
